Owen, Owen & Campbell.

UNITED STATES PATENT OFFICE.

JACOB H. RIZOR, OF VAN WERT, OHIO.

JOINTER-BEAM.

1,150,064.

Specification of Letters Patent. Patented Aug. 17, 1915.

Application filed September 4, 1914. Serial No. 860,172.

To all whom it may concern:

Be it known that I, JACOB H. RIZOR, a citizen of the United States, and a resident of Van Wert, in the county of Van Wert and State of Ohio, have invented a certain new and useful Jointer-Beam; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 My invention relates to jointers for breaking the surface in advance of plows.

It has particular reference to jointers when used in connection with rolling colters and it has for its object to provide a means 20 for so supporting the jointer relative to the rolling colter and plow so that sod, roots or stocky fertilizing material such as corn stalks and the like will not clog and bind between the rolling colter and the jointer. 25 An adjusting means is also provided so that the relative position of the two may be varied according to the character of the surface of the ground and the growth of weeds or the condition of the roots and sod 30 or material lying on the surface thereof to be plowed over.

The invention may be contained in many forms of constructions usable for different purposes, all of which come within the pur- 35 view of my claims hereinafter appended. To show the practicability of my invention, I have selected one of such constructions as an example and shall describe it hereinafter. The construction selected is illustrated in 40 the accompanying drawings.

Figure 1 of the drawing, is an illustration of the rolling colter, the jointer and the plow. The plow beam is shown broken away for convenience of illustration and the sup- 45 porting frame is omitted. Fig. 2 is a rear view of the rolling colter and the jointer. Fig. 3 is a top view of the rolling colter and the jointer.

1, is the plow.
50 2 is the plow beam.

3 is the rolling colter which is supported on the frame, 4, to which the plow 2 is connected in the manner well known in the art. 5 is the jointer which is also connected to 55 the frame 4.

The rolling colter is located in advance of

the plow 1, and cuts the ground which is subsequently turned over by the plow share. The colter is pivotally connected to a pin 10 by means of a bifurcated arm 11. It is 60 secured in position between the shoulder 12 and the split pin 13. The jointer 5 is supported on a beam 15. The beam 15 has a portion 16 which extends vertically upward as at 16. The jointer is secured to the portion 16 by means of the clamping collar 17. It is adjustably located in position by means of the key bolt 18. The jointer may be adjusted by shifting the collar 17 either angularly on the vertical portion 16 or longitudinally along the vertical portion. 70 The beam 15 is also provided with a portion 19 which extends horizontally well above the top of the rolling colter 3 at the delivery point of the jointer. This leaves a considerable space 21 between the beam and the top of the rolling colter so that if material is carried upward by the breaking action of the jointer and the cutting action of the rolling colter, it will have full opportunity 75 to escape from the rolling colter and the jointer and its supporting beam. The horizontal portion 19 extends from the vertical portion 16 to an inclined portion 20.

The beam is pivotally connected to the 85 pin 10. The end of the beam is provided with two ears 25 and 26. The pin extends through openings formed in the ears 25 and 26. The ears are located on each side of the head 14 of the bifurcated arm 11. The 90 arm 15 may be adjusted angularly with reference to the bifurcated arm 11. This is accomplished by means of a machine bolt 27 which extends through an enlarged portion of the end of the beam 15 and presses 95 against the head 14 of the bifurcated arm slightly to the rear of the axis of the pin 10. By screwing the bolt 27 the beam 15 is pushed angularly outward with respect to the arm 11. The bolt 27 may be directed 100 angularly inward as shown in Fig. 3. The beam 15 is locked in position with reference to the arm 11 by means of a threaded U-bar or by a pair of cross-bars 28 which are clamped together by a pair of bolts 29 105 which clamp the beam 15 to one of the furcations of the arm 11 after the beam 15 has been adjusted by means of the bolt 27.

In the jointers now known in the art, the sod clogs in between the jointers and the 110 colters which frequently causes the beam on the jointer to break and requires the user

of the plow to frequently stop in his work and clean out the material which collects in between the two or repair the jointer or replace the jointer beam.

5 The construction selected and described, may be greatly varied in the arrangement and manufacture of its parts and in the substitution of elements having equivalent functions and such modifications may be 10 used for many varied purposes and still contain the invention.

Having thus described my invention, what I claim as new, and desire to secure by Letters Patent, is,—

15 1. The combination of a rolling colter and a jointer, a beam for supporting the colter and a beam for supporting the jointer, the beam of the jointer having ears overlapping the sides of the end of the beam 20 of the rolling colter, and a pin extending through the ears of the beam of the jointer and the end of the beam of the rolling colter.

25 2. The combination of a rolling colter and a jointer, a beam for supporting the rolling colter and a beam for supporting the jointer, the end of the beam of the jointer being bifurcated and overlapping the end 30 of the beam of the rolling colter, a pin extending through the ends of the beams for

pivottally supporting the beams and a threaded bolt extending through the end of the beam of the jointer and abutting the end of the beam of the rolling colter and located substantially tangential to the surface 25 of the pin.

3. The combination of a rolling colter, a jointer, a bifurcated arm for supporting the rolling colter, a beam for supporting the jointer, a pin extending through the heads 40 of the arm and beam, a bolt for adjusting the beam relative to the arm and means for clamping the arm and beam together.

4. The combination of a rolling colter, a jointer, a bifurcated arm for supporting the 45 rolling colter, a beam for supporting the jointer, a pin extending through the heads of the arm and beam, for pivotally connecting them, a bolt located to the rear of the axis of the pin for adjusting the beam relative to the arm and a clamping means 50 for clamping the beam to one of the furcations of the arm.

In testimony whereof, I have hereunto signed my name to this specification in the 55 presence of two subscribing witnesses.

JACOB H. RIZOR.
